UNITED STATES PATENT OFFICE.

KENNETH W. DAUGHDRILL, OF AUSTIN, TEXAS.

ELECTRIC SIGN.

1,401,886.

Specification of Letters Patent. Patented Dec. 27, 1921.

Application filed February 11, 1919. Serial No. 276,382.

To all whom it may concern:

Be it known that I, KENNETH W. DAUGHDRILL, a citizen of the United States, residing at Austin, in the county of Travis and State 5 of Texas, have invented new and useful Improvements in Electric Signs, of which the following is a specification.

This invention relates to the method of making and the novel construction of illuminating signs of that class in which a plate having transparent letters or characters thereon is placed before a lighting medium so that the rays of light will pass through the transparent portions.

15 The principal object of the invention is to provide small protuberances on the plate which outlined the letters or characters and which are translucent so that the sign can be read at night, when illuminated, or during the day.

The invention also consists in certain other features of construction and in the combination and arrangement of the several parts, to be hereinafter fully described, illustrated 25 in the accompanying drawings and specifically pointed out in the appended claims.

In describing my invention in detail, reference will be had to the accompanying drawings wherein like characters denote like 30 or corresponding parts throughout the several views, and in which:—

Figure 1 is a front view of a sign constructed in accordance with this invention.

Fig. 2 is a view of the rear face of the 35 sign plate.

Fig. 3 is an enlarged section on line 3—3 of Fig. 2.

Fig. 4 is a rear view of the sign box.

Fig. 5 is a section on line 5—5 of Fig. 4.

40 In these views, 1 indicates a frame constructed similar to a picture frame. 2 indicates the sign plate, having the sign printed on its front face in any suitable manner. This plate fits in the frame, as shown. 3 45 indicates the box which is of pyramid form and has its base fitting in the frame and abutting the sign plate. The parts are held together by the upper and lower latches 4 so that said parts may be separated when 50 desired. I prefer to make the box from a single strip of material, which is bent into suitable form and has its meeting edges suitably screwed together. The inner surface of the box is painted with a coating of any suitable 55 reflecting material. An electric light socket 5 is secured to one of the inner faces

of the box to receive an electric lamp 6, the wires from which may lead to any suitable source of current. If desired this socket may be provided with the well known type 60 of flasher attachment so as to make the light intermittent.

The sign plate is first printed with the sign which it is to contain and this plate may be made of metal, cardboard or any 65 other suitable material. The letters or characters which are to be illuminated are then outlined by a series of holes punched through the plate, as at 7. A strip 8 of cloth, paper or other suitable material that will 70 stretch and is translucent, is pasted to the back of the plate, over said holes. Portions of the strip, while still wet, are then pushed through the holes to form protuberances 9. These protuberances project from the printed 75 face of the plate so that the letters can be easily seen during the day and at night, when the box is illuminated, the said protuberances will give the effect of a plurality of small electric light bulbs outlining the 80 letters. When the adhesive with which the strip is coated becomes dry the protuberances will retain their shape even though the plate is subjected to rough handling.

I find it desirable to outline the letters 85 composing the words of the sign that are not to be given the prominence of the main word or words by small holes 10 and pasting strips 11 on the back of the sign plate over said small holes but this strip is not to be punched 90 through the holes.

It will thus be seen that an attractive and effective sign is produced which can be manufactured to sell at low cost. While the sign is mainly designed for indoor use it may be 95 used out of doors by treating the face of the sign and the protuberances with a waterproofing composition or covering the face of the sign with glass.

Having thus described my invention, what 100 I claim is:—

1. The herein described method of forming a sign plate consisting in first outlining the sign characters on the plate by a series of holes, pasting a strip of translucent material having an adhesive coating on one face thereof on the rear of said plate over said holes and finally forcing the material through said holes to form hollow protuberances on the front face of the plate. 105

2. The herein described method of forming a sign plate consisting in first outlining

- the sign characters on the plate by a series of holes, pasting a strip of translucent and flexible material on the rear of said plate over said hole after treating said strip with 5 a stiffening and adhesive solution and finally forcing the material while still wet through the holes to form hollow protuberances on the front face of the plate.
3. A sign plate having the characters 10 thereon outlined by a series of translucent hollow protuberances formed from flexible material treated with a stiffening solution and means for illuminating said protuberances.
- 15 4. A sign plate having the characters

thereon outlined by a plurality of holes and hollow protuberances of flexible material treated with a stiffening solution projecting from said holes.

5. A sign plate having the characters 20 thereon outlined by a plurality of holes and a strip of cloth having an adhesive coating on one face thereof pasted on the rear of said plate over the holes with portions of the strip forced through the holes while the 25 coating is still moist to form hollow protuberances.

In testimony whereof I affix my signature.

KENNETH W. DAUGHRILL.
